ATTORNEY.

UNITED STATES PATENT OFFICE

JOSEPH R. McLELLAN, OF WICHITA, KANSAS

INCINERATOR

Application filed October 16, 1926. Serial No. 142,140.

My invention relates to incinerators.

The object of my invention is to provide an incinerator having two fire pots, one for garbage, and the other for débris or the like.

5 A further object of my invention is to construct an incinerator that is simple to construct and assemble, eliminating excess cost.

A still further object of my invention is to provide an incinerator such that the garbage 10 may be consumed by the débris positioned in the lower fire pot.

A still further object of my invention is to provide a gas burner as an assurance for the incineration of the garbage.

15 A still further object of my invention is to provide an incinerator having separate openings for the garbage and débris fire pots.

A still further object of my invention is to provide a simple means for entrapping vermin, including flies, consuming them in the burning process.

These and other objects will hereinafter be more fully explained.

Referring to the drawings:

25 Fig. 1 is an elevation of the incinerator.

Fig. 2 is a top view of Fig. 1.

Fig. 3 is a vertical section through the incinerator taken on line 3—3 in Fig. 2 looking in the direction of the arrows.

30 Fig. 4 is a cross section taken along line 4—4 in Fig. 3 looking in the direction of the arrows.

Fig. 5 is a transverse sectional view of Fig. 3 showing the gas burner and a modified 35 construction for the débris fire pot, said view taken on line 5—5 in Fig. 3 looking in the direction of the arrows.

Fig. 6 is an enlarged fragmentary sectional 40 view showing the assembly and supporting means for the débris fire pot.

Fig. 7 is an enlarged sectional view showing the relative position and assembly of the hood, the garbage fire pot, and the shell of the incinerator.

45 Fig. 8 is an enlarged fragmentary elevation of the side of the incinerator having the vermin trap hood illustrated, the view being taken from the line 8—8 in Fig. 1 looking 50 in the direction of the arrows.

Fig. 9 is an inside view of the trap mechanism.

Fig. 10 is a sectional view taken along the line 10—10 in Fig. 8.

Referring to the drawings in detail, 1 is a shell being cylindrical in form and having an annular ring 2 rigidly attached by means of rivets 3 to said shell. The said ring functions as a bearing for a fire pot 4 which has an annular flange to engage on the edge of the ring; said fire pot being frusto-conical in shape and having radially positioned openings 5 through the wall thereof to function as vents for the burning débris. The walls of the pot may be solid as shown in Fig. 5. The vent required would then be through the dump grate.

Positioned on the lower end thereof is a dump grate 6 pivotally mounted on diametrically positioned bearings 7. The said grate is equipped with a weight 8 on one side thereof, and a lug 9 on the opposite side. The weight is to properly position the grate closing the lower end of the fire pot, and the lug is a stopping means to engage on the edge of the opening to insure proper position for retaining the contents therein, and being carried by the pivots the grate will rock as means for dumping the ash accumulation to the storage space as at A shown in Fig. 3.

Resting on the fire pot is a lining 9' having outwardly extending flanges as at B as means for spacing the lining from the shell as at C. The said lining extending upward to a distance above the lower end of the garbage fire pot 10 hereinafter described. The lining functions as a heat resisting means protecting the shell of the incinerator as there is greater heat from the débris than from the garbage. The fire pot 10 is a frusto-conical shaped member having openings 11 spaced in the side thereof. The said openings are radially positioned from the apex of the cone. The said fire pot has an annular flange as at D which is adapted to engage over the upper end of the shell as hanging means therefor. The lower end of the pot is equipped with a dump grate 8', the same as that of the débris fire pot as means for discharging the ash accu-

mulation into the débris fire pot and from thence to the storage A.

Positioned on the top of the incinerator is a hood 12 being preferably made of cast iron and having an annular flange and bearing E 5 to fit snugly on the D member of the garbage fire pot 10. The said hood being frusto-conical has an annular flange 13 on the upper end thereof to receive a pipe 14 as smoke conveying means. Positioned in the hood 10 is a door 15 pivotally attached as at 16 and adapted to swing upward in the direction of the arrows.

Positioned in the side of the incinerator 15 between the fire pots is a door 16' hingedly connected to one side as at 17, and having a suitable catch as a fastening means when closed. Concentrically positioned therein is a shutter 17' as vent controlling means. A 20 similar door 18 is positioned for the ash storage space below the débris fire pot as means of access to the ashpit, while the first said doors is a means of access through which the refuse is placed in the fire pot.

Positioned in the top of the shell in close 25 proximity to the top of the garbage fire pot is a plurality of openings 19 having flanged hoods 20 rigidly attached and extending below the lower edge of said openings, and 30 being spaced therefrom as shown in Fig. 10 permitting flies and the like to enter the openings in their upward travel during times when the incinerator is being filled, and void of fire.

Positioned on the inside of the shell and 35 opposite the hood is a grating 21 rigidly attached, the said grating extending over the opening functioning as a retarder for burning embers from the débris. As a means to 40 prevent flies from entering the pipe and passing outward therethrough I have placed a screen 22 over the pipe opening which is securely fastened to the hood, the said screen also functioning as a spark retarder, should 45 the mechanism be placed out of doors and have no chimney connection other than a short piece of pipe. It will be understood when the fire is started the vermin are consumed with the débris. The mechanism 50 therefor functions as a fly trap in combination with its garbage and débris burning feature.

When the garbage fire pot has been well 55 filled and there being no débris as a kindling element to burn the garbage, or as an assistant with the débris I have provided a gas burner 23 to engage at the lower end of the garbage firepot, which when set in action tends to dry and gradually burn the contents. 60 As a controlling means for the burner I have provided a valve 24 in the gas pipe 25, the said pipe connecting with the house supply. Said gas pipe may also extend to the incinerator when placed outside the building.

Such modifications may be employed as lie within the scope of the appended claims.

Having thus described my invention, what I claim as new and desire to secure by Letters Patent is:—

1. In an incinerator of the class described, a shell having a frusto-conical firepot with a plurality of elongated openings through the wall thereof to function as vents, said firepot having flanges to engage on the top of the shell as supporting means therefor, a second frusto-conical firepot for débris, said firepot having a plurality of elongated openings functioning as vents, spaced below the center of the shell and carried thereby, a lining resting on the upper rim of said firepot, said lining extending a short distance above the lower end of the first said firepot, a door as means of access to each of said firepots, and a gas burner intermediately positioned to the said firepots.

2. In an incinerator of the class described, a cylindrical shell having a garbage firepot in the upper end thereof and a door as means of access thereto, a second firepot for débris near the lower end of the shell and a lining extending upward a short distance from the firepot, a door as means of access to last said firepot, a pair of openings diametrically positioned near the upper end of the shell and an outwardly extending hood for each, and a grating placed over each of the openings and being on the inside of the shell.

JOSEPH R. McLELLAN.
